United States Patent Office.

WILLIAM STODDARD, OF WINONA, MINNESOTA.

Letters Patent No. 81,957, dated September 8, 1868.

IMPROVEMENT IN FANNING-MILLS.

The Schedule referred to in these Letters Patent and making part of the same.

TO ALL WHOM IT MAY CONCERN:

Be it known that I, WILLIAM STODDARD, of Winona, in the county of Winona, and State of Minnesota, have invented a new and useful Improvement in Fanning-Mills; and I do hereby declare that the following is a full, clear, and exact description thereof, which will enable others skilled in the art to make and use the same, reference being had to the accompanying drawings, forming part of this specification, in which—

Figure 1 represents a sectional elevation, taken on the line $z z$ of fig. 2.

Figure 2 represents a horizontal section on the line $y y$ of fig. 1, and

Figure 3 represents a detail view, showing one of the screws, and the spouts leading thereto.

Similar letters of reference indicate like parts.

The object of this invention is to provide an improved fanning-mill for cleaning grain.

It consists of an improved agitating-apparatus, for facilitating the feeding of the grain from the hopper.

Also an improved apparatus for separating oats or other long grain from wheat.

Also, in combination therewith, of an improved screening-apparatus, for separating cockle and other small grains from the wheat.

A represents an oscillating feeding-bar, arranged under the mouth of the hopper on a shaft, which is actuated by a vibrating forked arm, B, which takes on an eccentric on the shaft of the fan-blower.

C represents a curved screen, provided with holes of sufficient diameter to allow the grain to fall through, but which are too short to allow oats, rye, or other long grains, to pass, unless they happen to rise up sufficiently to be presented endwise, for the prevention of which an endless apron, D, is provided, and arranged to move so near to the screen C as to effect the desired object.

The chaff and light material are delivered over the chute E, being separated from the grain in its vertical descent through the blast of air from the fan, from the hopper to the screen C.

The oats and other similar material which are separated by the screen are delivered over the chute F, and the grain is delivered by the chute G either to the spout H or I, the valve K determining which. By the spout H it is delivered to the rotating screen L, and by the spout I to another screen M, which may have finer meshes than the screen L.

The screens L and M may be operated by a cord, N, from the crank-shaft, or in any other suitable manner. Having thus described my invention, I claim as new, and desire to secure by Letters Patent—

1. The combination, with the hopper of a fanning-mill, of the oscillating feeding-bar A, substantially as and for the purpose described.

2. The combination, with the screen C, of the endless apron or belt D, substantially as and for the purpose described.

3. The rotary screens L and M, arranged as described, in combination with chute G, screen C, and fan-blower, substantially as and for the purpose described.

WILLIAM STODDARD.
